UNITED STATES PATENT OFFICE

HARRY LANSING CAREY, OF RICHMOND HILL, NEW YORK, ASSIGNOR TO ILLUMINATED ARROW CORPORATION, OF NEW YORK COUNTY, NEW YORK, A CORPORATION OF NEW YORK

TRAFFIC INDICATOR

Application filed January 14, 1931. Serial No. 508,770.

This invention relates to improvements in traffic indicators and especially to improvements in the arrow type of indicator shown and described in Letters Patent No. 1,431,932, dated October 17, 1922. The present improvement is particularly adapted for use as a stationary traffic indicator on street corners where it is desirable to denote one way traffic. It is also adapted to show a sign such as the name of a street or other designation. It is adapted to guide the traffic from town to town. It is also adapted for indoor use such as to guide the traffic to given points.

The objects of the present improvement are mainly to better distribute the light rays and lighting effect evenly or more uniformly from the middle part toward the point of the arrow and also from the middle part to the tail of the arrow. This is accomplished by making the arrow a greater width at the middle part where the lamp is located than at the point and tail, and also by widening the light slots gradually from the middle part toward the point and from the middle part to the end of the tail. The even distribution of light rays is further assisted by the use of reflectors both in the head and the tail part of the pointer.

Another object of my present form is to improve the means for permitting ready access to the lamp for the purpose of renewing the bulb or bulbs and to facilitate this, I provide a removable section such as the one described in the drawings. This removable section also permits the polishing and cleaning of the interior of the arrow or pointer.

The drawings illustrate a device embodying my invention as hereinafter claimed.

In the drawings,
40 Fig. 1 is a side elevation of my improved traffic indicator.

Fig. 2 is a top plan of the same.

Fig. 3 is a vertical section on the line 3—3, of Fig. 2.

45 Fig. 4 is a vertical section on the line 4—4 of Fig. 1, looking in the direction of the arrow.

The body of the arrow shown in the drawings comprises two halves 5 and 6 which are substantially alike, a removable section 7, and

a cap 8 which is secured to the cross piece 9 of the section 7 by means of a screw threaded into said cross piece. The section 7 has its end 10 fitting under the edge 11, and has its opposite projecting end 12 fitting in the recess 13. The half 6 of the body has a button 14 screwed thereon for more permanently holding the section 7 in place.

The light slots 15, 16, 17, 18 and 19 are made gradually wider as they approach the point, 60 and likewise the light slots 20, 21, 22 and 23 are made gradually wider as they approach the tail end. Light slots are also provided at 24.

Each of the halves 5 and 6 has a lower extension 25 at the middle part, the two together forming a tubular hollow part. Each of them is provided with a ledge 26 which serves as a stop when the device is mounted upon any suitable post or bracket having a member fitting in said tubular part 25. Each of the parts 25 is also provided with two ears 27 by which the two parts are screwed or bolted together.

The two halves 5 and 6 are also bolted together at 28, 29 and 30. The sides of the parts 5 and 6 may have cast thereon or otherwise suitably secured the words "One way" as shown at 29^a, or any other legend. The letters of the words or legends are perforated 80 to permit the light rays to pass through so that the legend may be easily readable at night.

The angular members 30^a are attached by bolts 31 and serve as reflectors in the head of 85 the arrow. Similar reflectors 32 are attached in the tail portion.

The perforations 33 in the letters of the legend are preferably increased in size from the middle part of the arrow toward each of 90 its ends. The purpose of this is to more evenly distribute the light. The usual position of the light bulb is indicated by the dotted lines 25^a in Fig. 3.

In using the term slots in some of the claims I intend that this term be broadly construed as including apertures of various forms which will accomplish the obvious purposes of this invention. I do not intend to restrict the invention to minor details which 100

may be changed without departing from the spirit of the invention.

I claim:

1. A traffic indicator comprising a hollow pointer formed with light slots in its side walls elongated in the pointive direction and a light internally so positioned that its rays will be projected in a manner to indicate the pointive direction regardless of visibility of the pointer itself, said slots being of greater width toward each end of said pointer than at the middle part. 70
  2. A traffic indicator comprising a hollow pointer formed with light slots in its side walls elongated in the pointive direction and a light internally so positioned that its rays will be projected in a manner to indicate the pointive direction regardless of visibility of the pointer itself, said pointer being wider at its middle part than at its ends, said slots being of greater width at the pointive end than toward its middle part. 75
  3. A traffic indicator comprising a hollow pointer formed with light slots in its side walls elongated in the pointive direction and a light internally so positioned that its rays will be projected in a manner to indicate the pointive direction regardless of visibility of the pointer itself, said pointer having a removable section in its wall at the middle part, said slots being of greater width at the pointive end than toward its middle part. 80
  4. A traffic indicator comprising a hollow pointer formed with light slots in its side walls elongated in the pointive direction and a light internally so positioned that its rays will be projected in a manner to indicate the pointive direction regardless of visibility of the pointer itself, said pointer having a part adapted to receive an internal lighting device and being wider, from side to side in a substantially horizontal direction, at said part than at the pointive end. 85
  5. A traffic indicating device comprising a hollow arrow-shaped pointer formed with light slots convergent to the line of pointive direction, and lighting means within said pointer, said pointer having a removable section in its top middle wall to permit the renewing of lamps and also the cleaning of the inside, said slots being of greater width at the pointive end than towards its middle part. 90
  6. A traffic indicator comprising a hollow arrow-shaped pointer formed with light slots in its side walls elongated in the pointive direction and a gradual widening of these convergent slots as they approach the head and the tail, a bulged middle part tapering off toward a point at the head and tail where reflectors are located, a side band containing the name or legend with apertures through each letter, and a removable section over the central portion where a light is internally so positioned that its rays will be projected in a manner to indicate the legend expressed pointive direction regardless of visibility of the pointer itself; and means for clamping said pointer to that on which it is mounted. 95
  7. A traffic indicator comprising a hollow pointer formed with light slots in its side walls which gradually widen as they converge from the bulged middle part toward the tapering ends where reflectors are located and a side band expressing the legend desired with apertures through each letter, and a removable cover over the middle part where a light is internally so positioned that its rays will be projected in a manner to indicate the pointive direction regardless of visibility of the pointer itself. 100
  8. A traffic indicating device comprising a hollow pointer formed with light slots in its side walls elongated in the pointive direction, said pointer having a part adapted to receive an internal lighting device and being wider at said part than at the pointive end, said slots being wider as they approach the pointive end. 105
  9. A traffic indicating device comprising a hollow pointer formed with light apertures in its side walls elongated in the pointive direction, the apertures being larger as they approach the pointive end than at the middle part. 110
  10. A traffic indicating device comprising a hollow pointer formed with light apertures in its side walls elongated in the pointive direction, said pointer having a part adapted to receive an internal lighting device, and said apertures being smaller at said part than at the pointive end. 115
  11. A traffic indicating device comprising a hollow pointer formed with light slots in its side walls, both at its pointing end and at its tail end, and lighting means within said pointer intermediate of the slots in the pointing end and those in the tail end, said slots being open so as to permit the rays of light from said lighting means to pass freely through the slots in a manner to indicate the pointive direction regardless of visibility of the pointer itself, the light-emitting area of said slots being greater at the pointing end than at the middle part of said indicating device. 120
- In testimony whereof I have hereunto set my hand, this 14th day of January, 1931.
